US00D530695S

(12) United States Design Patent (10) Patent No.: US D530,695 S
(45) Date of Patent: * Oct. 24, 2006

(54) DVD RECORDER

(75) Inventor: Jung-Hyun Park, Seoul (KR)

(73) Assignee: Samsung Electronics Co., Ltd.,
Kyunggi-do (KR)

() Term: 14 Years

(21) Appl. No.: 29/241,754

(22) Filed: Oct. 31, 2005

(51) LOC (8) Cl. 14-01

(52) U.S. Cl. D14/136

(58) Field of Classification Search D14/135–136,
D14/156–157, 167–168, 193–198, 188, 357,
D14/445; 360/99.02, 99.07, 137; 369/75.11,
369/75.21, 77.21, 77.11; 720/612, 619, 647,
720/655; 455/344, 347–351

See application file for complete search history.

(57) CLAIM

The ornamental design for a DVD recorder, as shown and described.

DESCRIPTION

FIG. 1 is a top front perspective view of a DVD recorder showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view.

1 Claim, 4 Drawing Sheets
